UNITED STATES PATENT OFFICE

133,982

DESIGN FOR A HOT FOOD PURVEYING STORE

William A. Bryans, Denver, Colo.

Application April 22, 1941, Serial No. 100,556

Term of patent 3½ years

To all whom it may concern:

Be it known that I, William A. Bryans, a citizen of the United States, residing at Denver, in the county of Denver and State of Colorado, have invented a new, original, and ornamental Design for a Hot Food Purveying Store, of which the following is a specification, reference being had to the accompanying drawing, forming part thereof.

The essential features of my design reside in the three-step circular platform having a pair of vertically extending standards rising from the second step on opposite sides of the main portion of the store, said standards engaging ears projecting laterally from a point immediately under the projecting roof edge, all in combination with a main structure of the specific configuration shown.

I claim:

The ornamental design for a hot food purveying store, as shown and described.

WILLIAM A. BRYANS.
